Primary Examiner — Kevin R Rudzinski*Assistant Examiner* — Paul D Bohannon(74) *Attorney, Agent, or Firm* — Taft Stettinius & Hollister LLP; Stephen F. Rost(57) **CLAIM**

The ornamental design for a furniture and animal crate assembly, as shown and described.

DESCRIPTION

FIG. 1 is a perspective view of one embodiment of a furniture and animal crate assembly;

FIG. 2 is a leftside elevational view thereof;

FIG. 3 is a rightside elevational view thereof;

FIG. 4 is a top plan view thereof;

FIG. 5 is a bottom plan view thereof;

FIG. 6 is a back view thereof; and,

FIG. 7 is a front view thereof.

The broken lines shown in the drawings are for the purpose of illustrating portions of the article and form no part of the claimed design.
